SIGNORS, BY MESNE ASSIGNMENTS, TO JESSIE B. BIBBER, OF PORTLAND, MAINE.

MACHINE FOR HOOKING RUGS AND THE LIKE.

Application filed May 19, 1925. Serial No. 31,436.

To all whom it may concern:

Be it known that we, JOHN A. BORROWS and CHESLEY T. SABINE, citizens of the United States, and residents, respectively, of 5 Portland, in the county of Cumberland and State of Maine, and Lewiston, in the county of Androscoggin and State of Maine, have invented new and useful Improvements in a Machine for Hooking Rugs and the like, of 10 which the following is a specification.

Our invention relates to a portable machine employed in the manufacture, principally, of certain kinds of rugs of which the base or body is composed of a sheet of burlap 15 or other fabric and through which strips of cloth, string or other pliable material is woven or threaded to form a substantially solid facing on the upper or tread side of the rug.

20 The especial object of our invention is to provide a device operable by any convenient power means for doing that work, which in the rug making art is termed "hooking", in a rapid, accurate and automatic manner, 25 the operator simply keeping the machine supplied with the hooking material and guiding it over the surface of the sheet of material to be hooked.

Another object is to provide means for 30 varying the length of the stitch, or the distance between the consecutive hookings, so that either a firm or loose facing may be obtained.

A still further object is to construct a machine with which it is possible to produce 35 different depths of facings, so that a thick or thin rug may result.

And in general, our object is to supply the rug hooking trade with a portable, easily 40 operated and strongly built machine in which is incorporated facilities for operating the power actuating elements with the hand, of the operator, which does the guiding of the machine, and one which is adaptable to 45 the use of a great variety of material with which to do the hooking work.

Other objects will be apparent from reading the specification when taken in connection with the accompanying drawings where- 50 in a preferable embodiment of our invention is illustrated, and in which all characters of reference represent similar parts throughout all the different views.

In the drawings,—
55 Fig. 1 is a front elevation of the machine;

Fig. 2 is a sectional elevation, taken on line 2—2, Fig. 1;

Fig. 3 is a front elevation of the crank disc, connecting rods and a portion of the slides;

Fig. 4 is a section taken on line 4—4, 60 Fig. 2;

Fig. 5 is a section taken on line 5—5, Fig. 2;

Fig. 6 is a section taken on line 6—6, 65 Fig. 2;

Figs. 7, 8 and 9 are sections showing different positions of the needle and follower during the operation of hooking;

Figs. 10 and 11 show the result of changing the angle between the presser-foot and 70 the adjustable leg;

Figs. 12 and 13 are perspective views of the presser-foot and adjustable leg, respectively;

Fig. 14 is a rear elevation of the clutch 75 connecting rod;

Fig. 15 is a section through the upper part of the body of the machine, and the adapter used in making connection to a flexible shaft for actuating the hooker; 80

Fig. 16 is an inverted plan of the drive thimble;

Fig. 17 shows the machine mounted on the operating table and in a position as used 85 in the hooking work, and

Fig. 18 shows the slides as they may be equipped with more than one needle and follower.

Referring to the Figs. 1 and 2, 1 represents the cylindrical portion of the body or 90 frame of the hooker, 2 a bearing extending through the rearward closed end and 3 a cover, attached to the cylinder by the screws 4.

Depending from the under side of the 95 cylinder is a tubular portion, the outside of which is formed into the shape of a handle or hand-grip 5, and with the bore, 5', extending therethrough. Another tubular projection, 6, extends upwardly from the top 100 side of the cylinder and contains the drive and clutch parts.

Journalled in the bearing 2 is the shaft 7 and fixed on the inner end of this shaft is the crank-disc 8. A nut 9 serves to hold the thrust of the shaft and keep it in place, longitudinally, in the bearing. 105

Cut on the side of the disc, adjacent the bearing, is a bevel gear 10, which is adapted to engage the bevel pinion 11, the latter 110

fixed on the shaft 12. This shaft (12) continues upwardly from the pinion, through the bearing 13, and is journaled at its upper end in the drive-sleeve 14 which has two flanges, 14' and 14'', shouldering on the upper and lower ends, respectively, of the split collar 15. This collar (15) is fixed in the bore 6' by the set screws 16, and serves to hold the sleeve 14 against vertical movement within the projection 6, although allowing the former to rotate within the latter at 17.

On the lower end of the drive-sleeve (14) is a hub 18, having a key-way 19 cut diametrically across its face. On the upper end of the clutch-ring 20 are keys 21, and these may at certain and predetermined times engage the key-way 19 on the drive-sleeve. At 22 is a feather, or travelling key, which is fixed in the clutch-ring 20 and adaptable of length-wise movement in the key-way 23 in the shaft 12.

Projecting from each end of the clutch-ring 20 are flanges 24, and operating between these and on both sides of the clutch-ring body is a bifurcated lever 25 oscillatively hung on the pin 26 which is fixed in the ears 27.

A bearing 28 may be provided for taking care of the thrust, in one direction, of the shaft 12.

Fixed on the disc 8 is a crank-pin 29 and operating thereon is the connecting-rod 30. On an extended portion of this pin 29, 29', 35 is fixed a link 31 extending diametrically across the face of the disc and having on its opposite end a crank-pin 32 on which operates the connecting-rod 33,—the disc together with the two crank-pins and the link 40 constituting a double-throw crank.

The lower ends of these connecting-rods, 30 and 33, are oscillatively attached to two slides, 34 and 35, by means of pins 34' and 35', respectively. By reference to Fig. 5 45 it will be observed that these slides are preferably made rectangular in cross section, the two being adjacent and reciprocable within the square bore of the bushing 36 which is made in halves for the purpose of taking care of the lateral wear between the slides 50 and bushing and also to facilitate and simplify their manufacture. The bushing is held in place within the hand-grip portion of the body by the screws 37.

Secured in any convenient manner to the lower end of the slide 35 is a needle 38 having a channel 38' formed on its forward side for the purpose of partially enclosing the rag or string used in the hooking operation 60 while the needle is passing through the sheet being hooked, and secured to the lower end of the slide 34 is a follower 39, the lower end, for a spaced distance upwardly, being very thin and flexible and with a considerable inclination toward the needle. A chan-

nel 38'' is cut on the rearward side of the needle (38) to receive this follower (39) at certain times during the reciprocation of these two members. An eye 40, through which the hooking material may be reeved, is made on the lower end of the needle which is also slightly inclined in the direction in which the machine is fed in operating.

Adjustably secured to the rearward side of the hand-grip 5, by means of the screws 41' which operate in the slot 41'', is a leg 41 which may be raised or lowered on the handle a certain amount.

Jointedly secured to the lower end of the leg (41) is a presser-foot 42, the two members being locked in any desired angular relation, one with the other, by means of the bolt 42'. An opening 43 is cut in the presser-foot through which the needle and follower may operate. The presser-foot is intended, always, to lie flat on the surface of the rug while the hooker is operating, and any change in the angular relationship between the presser-foot and the leg will result simply, and solely, in a change in the inclination of the leg.

In Fig. 15 we have shown a conventional method of attaching a flexible power shaft to the drive-sleeve 14. An adapter 44, to which the casing 45 of the flexible shaft 46 is secured, is threaded on to the upper end of the tubular projection 6. By means of the keyed end 46', of the flexible shaft plug, engaging a key-way 47 in the end of the drive-sleeve 14, the latter may be revolved through the agency of the shaft and any suitable prime mover,—such as the motor shown in Fig. 17.

In operating the hooker it is very desirable to have instant control over the starting and stopping of the power actuation. We have provided for this by mounting on the hooker, at a convenient position above the handle 5, a trigger shaped lever 48, pivoting it on the pins 49. This lever (48) is bifurcated, and the two branches of the bifurcation surround the body of the hooker and extending rearwardly enclose, by a pivoted connection at 51, the lower end of the connecting-rod 50. This member (50) extends upwardly and makes pivotal connection at 52 with the lever 25. A slot 53, in the connecting-rod 50 allows the latter to surround the bearing 2. A spring 54 normally holds the parts comprising the clutch operating mechanism in the position shown in full lines, Fig. 2,—the spring (54) being seated in pockets,—one, 55, in the bearing 2, and the other, 56, in a projection on the connecting-rod 50.

Whenever there is rotatable movement in the flexible shaft 46 the drive-sleeve 14 likewise is under rotation, but as the parts are positioned in Fig. 2 (full lines) no other elements are active. A slight pressure on

the trigger 48, however, will lift the clutch-ring 20 and cause it to engage the drive-shaft 14 and act to rotate the shaft 12, which, through the agency of the interconnecting parts, will reciprocate the slides carrying the needle and follower.

By reference to Figs. 7, 8 and 9, the method of "hooking" the rag or string stock through the sheet or base of the rug may be seen. In Fig. 7 the loaded needle is about to descend to the sheet. As it falls the follower rises, so that in Fig. 8 we have illustrated the position of the parts after one half the cycle of the cranks has been made. On the upward stroke of the needle the rag will loop, as seen in Fig. 9, but just previous to the complete withdrawal of the needle from the sheet the follower is starting to act to straighten out the loop,—the follower now being on the downward movement,—and by the time the needle has reached its upward limit of travel the follower will have travelled its limit in the opposite direction and exercised its function as a loop gauge or straightener, and thus one full cycle of the cranks is completed and the parts are again returned to the position shown in Fig. 7.

By raising or lowering the leg 41 on the hand-grip 5 a longer or shorter loop, respectively, will result, due, as will be obvious, to the fact that the needle and follower travel a greater or lesser distance, respectively, beyond the sheet in its downward passage through the same. This adjustability makes it possible to produce rugs of a great variety of thicknesses.

It is often desirable, and sometimes necessary, to vary the stitch, or the distance between the consecutive loops. This contingency arises when a change of the material with which the rug is to be hooked becomes imperative,—as when an intricate figure is to be woven into the design of the rug, or a more compact or a more loosely laid facing is called for. We effect this change of stitch by varying the angle between the presser-foot 42 and the leg 41. Fig. 10 illustrates the feeding action of the follower when the leg stands at a substantially right angle to the presser-foot. The full lines represent the follower about to enter the hole previously made by the needle. As it moves downwardly, the rearward side being inclined, the follower will force the presser-foot forwardly, so that at the termination of its full travel the former will have moved the latter to the position shown in dot and dash lines, Fig. 10.

It might appear from a casual inspection of the illustration that the reverse feeding action, or a movement of the presser-foot backwardly, might occur when the follower made its upward movement, and thus leave the machine in the position it originally

occupied. We have demonstrated that such is not the case in actual practice, however. On its downward movement the resistance of the follower through the sheet tends to lift the machine from the latter and allows it to slide ahead easily,—the inclined back of the follower in the perforation effecting the onward feed. On returning, the same resistance exists but it is now on the forward instead of on the rearward side of the follower and the tendency is to hug or draw the sheet upwardly against the under side of the presser-foot with sufficient force to overcome to a large extent the recession of the machine on the sheet. Then, too, the needle, entering the sheet in a new perforation somewhat in advance of the complete withdrawal of the follower from the old one, will give the machine a very slight movement ahead, due to the forward inclination of its point, and thus hold the machine from retracting in its feed,—the follower, meantime flexing as it withdraws.

If a coarser stitch is required the body of the hooker is inclined by the adjustment 90 of the bolt 42', so that the angle between the leg 41 and the presser-foot 42 is increased, as seen in Fig. 11,—the two characters "a" and "b" representing the distance between the stitches in Figs. 10 and 11, respectively. In general, it may be said that increasing the angle above referred to lengthens the distance between the consecutive stitches,—and vice versa.

Although we have illustrated the machine as a single unit hooker, it is apparent that several of these units might be constructed and placed side by side and operated as a multiple hooker. Or we may choose to so construct the device that more than one needle and follower may be mounted on each slide, placed side by side, cross-wise of the machine and multiply the number of stitches made at each reciprocation of the slides, as shown in Fig. 18.

The foregoing describes one, and that a preferable embodiment of our invention, but we may elect, and shall feel at liberty to make such minor changes in the design of parts as seem to us desirable, provided, however, that at all times the meaning and intent of the invention shall not be ignored and that all such deviations from the exact mechanical construction as herein set forth shall fall within the scope of the appended claims.

What we claim is:

1. In a machine for hooking rugs and the like, a body member, means on said body member for the purpose of grasping the same with the hand, a disc rotatably mounted within said body, a double throw crank on said disc, slides reciprocable within said body, rods connecting said crank with said slides, a needle fixed on one of said slides, a

follower fixed on another of said slides, the lower portion of said follower being bent toward said needle, a leg depending from said body and from the rearward side thereof, a presser-foot secured to the lower extremity of said leg and extending forwardly a spaced distance therefrom, and having an aperture therein in which said needle and said follower may operate, and means to vary the distance between consecutive stitches made by said machine.

2. In a machine for hooking rugs and the like, a body member, a handle subtending said body, slides adapted to reciprocate within said handle, means for actuating said slides, a needle, having an eye therein, fixed in the lower end of one of said slides, lateral flanges extending forwardly on said needle for the purpose of partially encompassing the hooking material as it passes through the sheet being hooked, a follower, located rearwardly of and with its lower portion inclined toward the said needle, fixed in the lower end of another of said slides, a leg secured to and depending a spaced distance from said handle, a presser-foot jointedly secured to the lower extremity of said leg and having an aperture through which said needle and said follower may actuate in the operation of said machine, and means for varying in predetermined degrees and at predetermined times the angular relationship between said leg and said presser-foot.

3. In a machine for hooking rugs and the like, a body member, a hand-grip downwardly disposed and integral with said body member, slides reciprocable within said hand-grip, means to actuate said slides, a needle having an eye therein and its pointed end inclined forwardly fixed in one of said slides, lateral flanges extending rearwardly to form a channel on said needle, a follower, located rearwardly of and with its lower portion for a spaced distance upwardly inclined toward said needle, fixed in another of said slides, a leg depending from and secured to said hand-grip, a presser-foot, a clamp bolt adapted to secure said presser-foot to said leg at any predetermined angle therewith, means for locating said presser-foot a predetermined and variable distance

from said hand-grip, whereby a longer or shorter loop may be had in the hooking operation, a clutch operable within said machine and adapted to engage and disengage the actuating power means therewith connected, and means incorporated in the structure of said machine whereby said clutch may be actuated by the hand of the operator which grasps the machine in operating.

4. In a machine for hooking rugs and the like, a body member of cylindrical shape, a depending portion from said cylinder and adapted to be used as a hand-grip by which said machine may be guided over the sheet to be hooked, a bearing in the closed end of said cylinder, a shaft journaled in said bearing, a disc fixed on said shaft, a double-throw crank mounted on said disc, connecting-rods adapted to operate over the pins on said cranks, slides reciprocable within the hand-grip portion of said machine, connecting means between said slides and said connecting-rods, a needle, having an eye therein and its free end for a spaced distance from the point forwardly inclined, fixed to one of the said slides, flanges on both the forward and rearward sides of said needle, a follower with its entering end for a spaced distance inclined toward said needle fixed to another of the said slides, a leg mounted on the end portion of said hand-grip, a presser-foot attached to the free end of said leg, means to fix said presser-foot in various and predetermined positions on said leg, relative to their angular relationship, means to lengthen and shorten in various and predetermined amounts the distance between the said presser-foot and the said hand-grip, a cover for the purpose of closing the open end of said cylindrical portion of said body, a drive-sleeve adapted to be under continuous rotation, means for actuating said drive-sleeve, a clutch, means to engage said clutch with said drive-sleeve and means whereby said clutch shall be automatically disengaged from said drive-sleeve whenever the machine is out of the operator's hand, substantially as described.

JOHN A. BORROWS.
CHESLEY T. SABINE.
